O. MIETH.

VIBRATOR.

APPLICATION FILED JUNE 16, 1915.

1,248,886.

Patented Dec. 4, 1917.

UNITED STATES PATENT OFFICE.

OTTO MIETH, OF CINCINNATI, OHIO, ASSIGNOR TO OHIO PATTERN WORKS, A PARTNERSHIP COMPOSED OF JOSEPH E. HAUSFELD AND VICTOR E. TRESISE, OF CINCINNATI, OHIO.

VIBRATOR.

1,248,886.

Specification of Letters Patent.

Patented Dec. 4, 1917.

Application filed June 16, 1915. Serial No. 34,407.

To all whom it may concern:

Be it known that I, OTTO MIETH, a citizen of the United States, and a resident of the city of Cincinnati, in the county of Hamilton and State of Ohio, have invented certain new and useful Improvements in Vibrators, of which the following is a full, clear, and exact description, reference being had to the accompanying drawings, forming part of this specification.

My invention relates to pneumatic vibrators or rapping devices such as are used in plate or bench molding to vibrate the bench plate or tub in separating the cope 15 from the drag or pattern, which vibrators are intended to take the place of an assistant in striking the plate or bench with a hammer, in order to loosen the sand.

The object of the invention is to provide a simple and effective vibrator which shall be airtight and jarproof, which shall require no unnecessary pipe connections or pipe fittings, which the molder can operate while standing in his natural position, and 25 which shall embody the complete mechanism including the air valve in a single casing adapted for ready attachment to the bench or tub.

My invention consists of that certain 30 novel construction and arrangement of parts to be hereinafter particularly pointed out and claimed, whereby the objects above set forth are attained.

In the drawings, 35 Figure 1 is a longitudinal vertical section of my improved vibrator.

Fig. 2 is a top elevation of the vibrator partly broken away to show the internal vibrator.

40 Fig. 3 is a plan view of the vibrator on a plate.

Fig. 4 is a front elevation of the vibrator on a bench.

Fig. 5 is a side elevation thereof.

45 Fig. 6 is a bottom plan view of the vibrator.

My vibrator is illustrated as attached to a molder's hand plate 1 (Fig. 3), and also to a molder's bench 2 (Figs. 4 and 5) in a modified form. In the prior art there have been various forms of vibrators attached to the plates or benches used by molders, but the difficulty, particularly in plate molding, has been that the valve for turning com-

pressed air off and on from the vibrator is 55 placed somewhere along the flexible hose or the pipe for air to the vibrator, and hence causes the operator to be constantly turning away from his work. In the vibrator to be described herein, the valve for the air 60 line is built into the vibrator itself, thereby permitting in bench molding a simple foot, knee or body presser device for controlling the air, and in plate molding permitting the vibrator to be employed as one of the 65 handles of the plate, as will be described.

The vibrator comprises a base plate 3 and a cylindrical casing 4 preferably integral therewith.

The cylindrical portion of the casing is 70 cored out lengthwise to form a cylindrical channel in which is mounted the pneumatic plunger 5 of the ordinary construction, provided with annular grooves 6. Ports 7 are formed in the cylinder to allow for the 75 inlet and exhaust of the compressed air from each end of the plunger. The compressed air to operate the pneumatic hammer is admitted through the passageways 8, 9, controlled by the valve 10, provided 80 with a valve stem 11, which extends so that its outer end projects slightly beyond the side wall of the casing.

In the older constructions above mentioned, in which the air valve is contained 85 in a separate casing, it is necessary to have pipe connections between the air valve and the vibrator, which connections must necessarily be maintained airtight, and in the ordinary construction being separated from 90 the vibrator proper, the air valve is very apt to get clogged up with dirt causing trouble in the operation of the device.

By locating this air valve in the cylindrical casing inclosing the plunger, these 95 difficulties are obviated, as well as permitting the easy air control to be now described.

The air valve chamber 13 is closed by the plug 14 which can be removed for the insertion of the valve. The air valve is held on its seat by the coiled spring 15 bearing between the plug and the head of the valve. The compressed air enters the valve chamber 13 through the passage 8, and the tube 105 16 for conveying the air from the compressor is secured over the pipe nozzle 17. The cylinder for the plunger 5 is open at one

end, which is closed by a screwthreaded plug 18 provided with a square head 19 for convenience in turning.

5 A coiled spring 20 bears on one end of the plunger 5 to normally hold the plunger at one end of the plunger chamber, so that the plunger will always be in position to be actuated by the compressed air.

Pivoted at one side of the base plate of 10 the vibrator, when it is to be used in bench molding, is a double bell crank lever 21, the vertical arm of which has pivotal connection with the dovetailed sliding bar 22, which is located in a channel 22^a in the top 15 of the vibrator cylinder. One of the horizontal arms of the bell crank is connected by a connecting rod 23 with a foot treadle 24, pivoted in a bracket 25, secured to the bench. The depression of the foot treadle 20 will rock the bell crank and cause the sliding bar to slide at its farther end over the top of the valve stem 11, which is arranged to extend out through the channel for the 25 sliding bar. This will cause the valve to be depressed and the air to rush into the vibrator chamber.

The end of the bar 22 is cut away at 26 to enforce an easy depression of the valve stem, and the other horizontal arm of the 30 bell crank is acted upon by a compression spring 27 to return the lever and slide bar to normal position whenever released.

Pivoted in ears 28 on the base plate is the curved plate 29. This plate is 35 provided with an extension 30 at one of its pivots (Fig. 5), which bears against the under side of the spring-pressed end of the bell crank lever so that the operator, pushing with his knee or other part of his body 40 against the plate 29, will also rock the bell crank lever to open the air valve.

By reason of my construction which mounts the controlling valve directly in the vibrator casing, I am able in this convenient 45 way to provide separate independent devices for opening the air valve,—one to be operated by the foot and the other by the knee or some other portion of the body.

In plate molding there is, of course, no 50 necessity for a foot or knee presser device. The plate is held in the hands of the operator in separating the mold or whenever vibration is desired. On the plate 1, shown, (Fig. 3) which has the usual hand holds 31,

31, at each side, my vibrator is to be attached by bolting the base plate to one of the hand holds. The hand vibrator will preferably be made smaller than the bench vibrator and its cylindrical casing can be grasped by the operator and used in holding 55 up the plate.

This method of attachment will bring the top, as it has been called, of the vibrator casing, in which the sliding bar 22 is channeled, into a position extending sidewise 60 away from the plate.

The sliding bar, at the end where it is cut away at 26 to form an incline for forcing down the air cut off, is also provided with a stud or finger hold. As the operator 70 grasps the cylinder with his palm over the sliding bar, he can easily use his thumb to push the bar into position to open or to close the air valve. Of course, in the hand hold vibrator, there will be no necessity for 75 the bell crank lever 21 and its spring 27, so these parts will be omitted.

In this latter special use of my new 80 vibrator, the great advantage of the self-contained air valve as far as its opening so the way for convenience of operation, is perhaps more apparent than in the use first mentioned. The non-clogging and non-leaking advantages are the same in both adaptations, as is self evident.

Having thus described my invention, what 85 I claim as new and desire to secure by Letters Patent, is:—

1. In a molder's vibrator, the combination with a casing, a vibrator therein, and air inlet therefor, a valve for the vibrator inclosed within said casing and having a stem, a sliding member on the casing, so mounted as to slide across the end of said valve stem to depress the same and to hold the valve depressed.

2. In a molder's vibrator, a casing, a vibrator within the casing, an air valve in the casing, a mounting plate for the casing extending laterally therefrom, and means for mounting the same on a molder's plate to constitute a handle therefor, and a sliding member on the casing for depressing the valve, located on the opposite side from the mounting plate and adapted to slide longitudinally of the casing to actuate the air valve.

OTTO MIETH.
